INVENTOR

David Pell.

By Joseph Koenig
ATTORNEY

UNITED STATES PATENT OFFICE.

DAVID PELL, OF ST. LOUIS, MISSOURI.

PICTURE FRAME.

Application filed August 8, 1924. Serial No. 730,940.

This invention relates to a certain new and useful improvement in picture-frames and the like.

My invention has for its chief object the provision of a picture-frame that is conveniently adjustable as to size to accommodate pictures of various sizes.

My invention has also for an object the provision of a picture-frame of the type stated in which certain of the frame-members are yieldingly secured together for operative holding engagement with the transparent-picture-cover of the frame.

My invention has for a further object the provision of a picture frame of the type stated that is simple and inexpensive in form and structure and neat and attractive in appearance.

And with the above and other objects in view, my present invention resides in the novel features of form, construction, arrangement, and combination of parts hereinafter described and pointed out in the claims.

25 In the accompanying drawing,

Figure 1 is a perspective view of a picture-frame embodying my invention;

Figure 2 is a front elevational view of the frame;

30 Figure 3 is an enlarged detail sectional view of the frame taken approximately on the line 3—3, Figure 2; and

Figure 4 is a front elevational view of a slightly modified form of picture-frame embodying my invention.

Referring now more in detail and by reference characters to the drawing, which illustrates both a preferred and a modified embodiment of my invention, 1, 1, designate 40 the longitudinal or side members or bars, and 2, 2, designate the lateral or end bars of the frame, all of which bars may be of wood, metal, or other suitable material and of suitable dimensions. Adapted for cooperation

45 with the bars 1 and 2, are so-called corner-members 3, each of which is also of suitable material and of suitable dimensions, and each of which is formed with oppositely disposed ways 4, 5, disposed upon different

50 planes so as to be non-intersecting and of dimensions to snugly correspond for slidable adjustment with the section of the bars 1, 2, respectively. As so constructed and formed, the side-bars 1 are fitted to extend length-

55 wise through the corner-ways 4 and the end-bars 2 are fitted to extend lengthwise through

the corner-ways 5, as shown, relative movement of the corner-members 3 upon the end-bars 2 effecting an adjustable spacing laterally of the frame of the side bars 1 and, correspondingly, relative movement of the corner-members 3 upon the side-bars 1 effecting an adjustable spacing longitudinally of the frame of the end-bars 2. Thus the several frame-members are relatively adjustable to 60 accommodate pictures or the like 6 and sections of glass or other transparent picture-cover members 7 of different size, which latter are, respectively, detachably and removably disposed at their opposite upper 65 and lower edges in recesses or rabbets 8 formed for the purpose upon the underface of said bars 2, as shown in Figure 3.

The normal snug, frictional engagement between the bars 1 and 2 and corner-members 3 serves efficiently to retain the same in relatively adjusted positions. Preferably, however, the end-bars 2 are yieldingly connected together by a pair of spaced elastic members preferably in the form of coiled 70 springs 9 lengthwise disposed longitudinally of the frame intermediate the side-bars 1, as best shown in Figure 1, which springs 9 function not only to yieldingly retain the end-bars 2 firmly in securing or holding engagement with the cover-member 7, but also, to retain the picture 6 in display position flatwise under the cover-member 7, as shown.

Preferably pivoted centrally upon the upper end-bar 2, is a suitable hook 10 and a 75 bar 11, whereby selectively the frame as a whole may be suspended upon a wall or as an easel with a cabinet-size picture supported on a table or the like, the bar 11 being preferably of telescopic sections for convenient 80 adjustment to vary the length of bar 11 to correspond with size adjustments of the several frame-bars 1 and 2.

And in Figure 4, the frame proper is pivotally displayed in a standing-frame comprising a base 12 and end-standards 13, each of which is also formed of telescopic sections for convenient adjustment to vary the size of the standing-frame in accordance with the adjusted size of the frame-proper to be displayed, the frame side-bars 1 having suitable recesses 14 to accommodate the pivot-pins 15 of the standards 13, as shown.

My new picture frame is simple in form, inexpensive of manufacture, neat in appearance, and substantially universally adjustable within the limits of the dimensions of

its particular parts to accommodate pictures and the like of varying sizes.

I am aware that changes in the form, construction, arrangement, and combination of the several parts of my new picture frame may be made and substituted for those herein shown and described without departing from the nature and principle of my invention.

10 Having thus described my invention, what I claim and desire to secure by Letters Patent is:

1. A picture-frame including a pair of side-bars, a pair of relatively movable end-bars, a cover-member adapted to removably rest at opposite edges upon the end bars, and elastic-members having connection with the end-bars for yieldingly retaining the same in engagement with the cover-member.

15 2. A picture-frame including a pair of

side-bars, a pair of relatively movable end-bars, a cover-member adapted to removably rest at opposite edges upon the end bars, and coiled springs having connection with the end-bars for yieldingly retaining the same 25 in engagement with the cover-member.

3. A picture-frame including a pair of side-bars, a pair of relatively movable end-bars, a cover-member adapted to removably rest at opposite edges upon the end-bars, a 30 picture removably disposed flatwise under the cover-member, and coiled springs having connection with the end-bars for yieldingly retaining the same in engagement with the cover-member and holding the picture under 35 the cover-member.

In testimony whereof, I have signed my name to this specification.

DAVID PELL.
